(57) **CLAIM**

The ornamental design for a sternum protector, as shown and described.

DESCRIPTION

FIG. 1 is a front perspective of our sternum protector showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a bottom elevation view thereof; and

FIG. 7 is a top view thereof.

FIG. 8 is a perspective view thereof being worn by a user according to one configuration;

FIG. 9 is a perspective view thereof being worn by a user according to another configuration; and,

FIG. 10 is a right side elevation view thereof being worn by a user according to another configuration.

The longer broken lines indicate stitching and form no part of the claimed design. The shorter broken lines show environment of structure and form no part of the claimed design. The dot-dot-dash broken lines shown in FIGS. 8 and 9 illustrate a user and form no part of the claimed invention.
